UNITED STATES PATENT OFFICE.

EDMUND P. ARPIN, JR., OF PORT EDWARDS, WISCONSIN.

ROTARY REFINER.

Application filed August 8, 1927. Serial No. 211,276.

This invention relates to a rotary refiner for refining wet, fibrous material, such as pulp, paper stock and the like.

It is an object of this invention to provide 5 a rotary refiner of simple rugged construction that may be used in the refining of fibrous material, pulp and paper stock and which embodies certain improved construction for the feeding of the fibrous material to the refining elements.

Other and further important objects of this invention will become apparent from the disclosures in the following description and appended claims.

15 In the accompanying drawings which illustrate a preferred embodiment of this invention and in which similar reference numerals refer to similar features in the different views:

20 Figure 1 is a vertical sectional view of a rotary refiner embodying the principles of my invention, with parts in elevation.

Figure 2 is a reduced sectional view taken on line II—II of Figure 1.

25 Figure 3 is a reduced sectional view taken on line III—III of Figure 1.

Figure 4 is an enlarged sectional view with parts in elevation, illustrating the feeding mechanism.

30 Figure 5 is a vertical sectional view with parts in elevation of a modified form of my device.

As shown on the drawings:

The reference numeral 1 indicates a casing 35 or casting adapted to be mounted upon a hollow base 2 and to house the refining elements. Said casing 1 is provided with a lower intake 3 for the admission of wet fibrous material, pulp, paper stock and the like, through an intermediate cylindrical portion 4 of said casing 1. An upper section 5 providing an outlet 6 is secured to said intermediate cylindrical section 4, by means of bolts 7. Said intermediate section 4 is formed with a recess 8 in which is positioned a lining 9 of abrasive material, such as stone, porous iron or the like. If the lining 9 is of stone, it is preferably composed of a plurality of segments secured in the recess 8 and presenting a cylindrical inner abrasive surface for coaction with the refining elements.

A vertical shaft 10 is suitably journalled in bearings 11 and 12 formed in the upper sec-

tion 5 and the lower portion of the casing 1 respectively. Said shaft 10 is provided with 55 a lower end 13 extending into the hollow base 2 and having secured thereto a gear 14 adapted to mesh with a worm gear 15 on a driveshaft 16. The driveshaft 16 may be driven by any suitable source of power, such as an 60 electric motor (not shown). At the intake end of the shaft, there is mounted an impeller 17 for drawing the wet fibrous material under suitable head into the refiner. Said impeller 17, as best shown in Figure 3, 65 is secured to the shaft 10 by means of a key 18 and is provided with spiral radial arms 19 extending to the inner surface of the intermediate casing section 4. Immediately above the impeller 17 and similarly keyed to said shaft 10, is mounted a lower plate 20 having circumferential openings 21, preferably semi-circular in section and closely adjacent the 70 ends of each of said impeller blades 19. An upper plate 22 of smaller diameter is similarly keyed to the shaft 10 and spaced apart from the lower plate 20 to include between said plates refining elements 23 and 24. Said refining elements 23 and 24 are pivotally and eccentrically mounted upon pins 25 extending between said plates 20 and 22 for rotation therewith. Each of said refining elements 23 and 24 comprises an irregularly shaped plate, formed either of stone or metal, and having an outer arcuate face 26 adapted 75 to conform with and bear against the inner face of the lining 9. The forward portion of each of said arcuate faces 26 curves away from the inner face of the lining 9 in the direction of rotation, as at 27, to form an acute angle 80 therewith. The various refining elements 23 and 24 are so positioned relative to the openings 21 that the stock is directed through said openings 21 by means of the impeller 17 and deflecting plates 28 against the forward faces 27 of said refining elements. The deflecting plates 28 (Figure 4), are formed on the plate 22 to partially surround the openings 21 and catch and direct the wet fibrous material impelled by the impeller blades 19 85 against the refining elements 23 and 24 as described.

It will thus be apparent that efficient means have been provided for feeding the stock to the refining elements. It is obvious that the 100 fibrous material will work between the arc-

- uate faces 26 of the various refining elements 23 and 24 and the inner surface of the lining 9 and will thus be subjected to a rubbing and defibering action. Centrifugal force will naturally tend to produce a grinding pressure between the respective arcuate faces 26 of the refining elements and the inner surface of the lining 9, due to the fact that said refining elements are pivoted eccentrically with respect to their mass. The speed of rotation of the shaft 10 may be adjusted to effect the desired refining action in a single rotary refiner of the type described or a battery of such refiners may be used in series. The curvature of the impeller blades 19 is set so as to effect the necessary rate of flow of fibrous material through the refiner and out through the outlet 6.

In the modified form of my refiner, illustrated in Figure 5, the central shaft 30 is disposed horizontally so that the refining elements 31 rotate in a vertical plane. Otherwise, the structure of the modified form of refiner is similar to that above described. The fibrous material enters through an inlet 32 and is directed by means of an impeller 33 through openings 34 in the plate 35 and by means of deflector plates 36 the fibrous material is deflected between the outer faces of the refining elements 31 and the inner surfaces of the abrasive lining 37. The refined stock is discharged through an outlet opening 38.

I am aware that many changes may be made and numerous details of construction may be varied through a wide range without departing from the principles of this invention and I, therefore, do not purpose limiting the patent granted hereon, otherwise than necessitated by the prior art.

I claim as my invention:

1. A rotary refiner for paper stock, pulp and the like, comprising a casing having inlet and outlet ports, a shaft journalled therein, an impeller secured to said shaft, a pair of spaced plates mounted upon said shaft, pins rigidly secured at their respective ends in said plates, refining members pivotally mounted upon said pins between said plates, one of said plates having openings, and deflecting means associated with said openings for directing stock between said refining members and said casing inner wall.

2. A rotary refiner for wet fibrous material, comprising a cylindrical shell having an inner abrasive surface, spaced plates rotatably mounted within said shell, eccentrically pivoted refining members mounted between said plates, one of said plates having circumferential openings, and deflecting means associated with said openings for directing material therethrough between the adjacent surfaces of said refining members and said shell.

3. A rotary refiner for wet fibrous material,

comprising a casing having inlet and outlet ports, a cylindrical lining for said casing having an abrasive surface, a shaft mounted axially of said lining and journalled in said casing, axially spaced plates secured to said shaft, one of said plates having peripheral openings, refining members pivotally mounted between said plates, said refining members having outer arcuate faces adapted to bear against the abrasive surface of said lining and an impeller on the intake side of said plates secured to said shaft for forcing material through said openings between the bearing surfaces of refining members and said lining.

4. A rotary refiner for wet fibrous material, comprising a casing having inlet and outlet ports, a cylindrical lining for said casing having an abrasive surface, a shaft mounted axially of said lining and journalled in said casing, axially spaced plates secured to said shaft, refining members pivotally mounted between said plates, said refining members having outer arcuate faces adapted to bear against the abrasive surface of said lining and an impeller on the intake side of said plates secured to said shaft for forcing material between the bearing surfaces of refining members and said lining, one of said plates having openings and deflectors associated with said openings for properly directing the material.

5. In a rotary refiner for wet fibrous materials, a cylindrical shell, a plurality of rotatable spaced refining members eccentrically pivoted with respect to the axis of said shell and their own mass and provided with arcuate outer faces adapted to contact and conform with the inner surface of said shell, said arcuate faces curving away from said shell surface in the direction of rotation of said members and means for directing material between said arcuate faces and said shell surface, including an impeller rotatable with said refining members and having blades terminating forwardly of said arcuate faces.

6. A rotary refiner for wet fibrous material, comprising a casing having inlet and outlet ports, a cylindrical lining for said casing having an abrasive surface, a shaft mounted axially of said lining and journalled in said casing, axially spaced plates secured to said shaft, one of said plates being of substantially the same diameter as the inner diameter of said cylindrical lining and having peripheral openings, deflector plates adjacent said openings and refining members pivotally mounted between said plates and adapted to bear against said abrasive surface.

7. A rotary refiner for wet fibrous material, comprising a casing having inlet and outlet ports, a cylindrical lining for said casing having an abrasive surface, a shaft mounted axially of said lining and journalled in said casing, axially spaced plates secured to said

shaft, one of said plates being of substantially the same diameter as the inner diameter of said cylindrical lining and having peripheral openings, deflector plates adjacent said openings, refining members pivotally mounted between said plates and adapted to bear against said abrasive surface, and an impeller sc-

cured to said shaft for directing material through said openings against said deflectors.

In testimony whereof I have hereunto subscribed my name at Port Edwards, Wood County, Wisconsin.

EDMUND P. ARPIN, JR.
